CLAIM

The ornamental design for a hip huggable cooler, as shown and described.

DESCRIPTION

FIG. 1 is a top front perspective of the hip-huggable cooler showing a new design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a bottom plan view with strap crossing the bottom;

FIG. 7 is a view similar to FIG. 6 but with the strap crossing the top as in FIGS. 1 and 2;

FIG. 8 is a front elevational view of another embodiment of my design—differing from that of FIGS. 1–7 in not having the quilted look seen prominently in FIGS. 1–5;

FIG. 9 is a front elevational view of yet another embodiment of our design—differing from that of FIGS. 1–7 in not having the quilted look as described above with respect to FIG. 8 and further not having the front mesh pocket of FIGS. 1–7; and,

FIG. 10 is a front elevational view of a further embodiment of our design—differing from that of FIGS. 1–7 in not having the quilted look and in not having the front mesh pocket.
